UNITED STATES PATENT OFFICE.

GEORGE H. REIMER, OF FULTON, ILLINOIS, ASSIGNOR TO PATENT NOVELTY COMPANY,
OF FULTON, ILLINOIS, A CORPORATION OF ILLINOIS.

DESIGN FOR A MAIL BOX.

Application filed February 27, 1929. Serial No. 30,234. Term of patent 14 years.

To all whom it may concern:

Be it known that I, GEORGE H. REIMER, a citizen of the United States, and a resident of Fulton, in the county of Whiteside and State of Illinois, have invented a new, original, and ornamental Design for a Mail Box, of which the following is a specification, reference being had to the accompanying drawing, forming a part thereof.

I claim:

The ornamental design for a mail box, as shown.

GEORGE H. REIMER.
